COMBINED MEMORANDUM PAD AND CONTAINER

Erik Westberg, Douglas, N. Dak., assignor of one-half to Alex Lind, Williston, N. Dak.

Application March 7, 1942; Serial No. 433,806

I Claim. (Cl. 281—2)

My invention relates to an improved combined memorandum pad and container, and the primary object of my invention is to provide a simple and efficient arrangement of this character which provides a roll paper memorandum pad devised in a convenient and attractive form, together with special compartments for holding cigarettes, shaving implements, and the like, whereby the device serves the dual purpose of providing traveling men and others with an efficient memorandum pad and container for the articles mentioned, all in a single unit.

Other important objects and advantages of my invention will be apparent from a reading of the following description taken in connection with the appended drawings, wherein for purposes of illustration I have shown a preferred embodiment of my invention.

In the drawings:

Figure 1 is a general front or top plan view showing the front cover open to expose the calendar and the roll paper memorandum pad, and with the cigarette compartment flap closed.

Figure 2 is a rear elevational view of the device with the rear cover open to show the mirror thereon and to expose the compartments for reception of toilet articles or the like, such as portions of a safety razor shown in phantom lines.

Figure 3 is a transverse vertical sectional view taken approximately centrally through Figure 2.

Figure 4 is a fragmentary plan view showing one end of the paper roll and its spool.

Figure 5 is a view of the shaft on which the spool is mounted.

Figure 6 is a perspective view of the spool.

Figure 7 is a perspective view of the paper retainer bar.

Referring in detail to the drawings, the numeral 5 generally designates the main body of the device which consists in the substantially parallel sided longitudinal walls 6 whose opposite ends are curved in accordance with the contour of the curved ends 7 and 8 which are secured to and between the curved ends of the side walls. The space between the ends 7 and 8 and between the side walls 6 is closed by the swingable front cover which is generally designated 10 and which itself has side walls 11 to meet the upper edges 9 of the main body side walls 6, with the web 12 between the side walls 11 and attached to their upper edges, curved downwardly at its opposite ends to merge into the curved end walls 7 and 8, as indicated in Figure 3 of the drawings.

Suitable hinge means 13 arranged at the inner sides of the wall portions 12 and 8, swingably

mount the front cover 10 to enable it to be swung to the open position illustrated in Figure 1 of the drawings. Adjacent the opposite ends of the front cover 10 is a rotatable catch button 14 which has a shank passing through the web 12 and equipped at the inner side of the web 12 with a projecting finger 15 adapted to engage under the front edge of the curved end wall 7 of the body 5 to retain the front cover in a closed position when desired.

Longitudinal ribs 16 run along the opposite walls 11 from a point adjacent the catch to a transverse ledge 17. The enclosure provided by the ribs 16 and the ledge 17 provide a receptacle for a number of calendar cards 18, which may be inserted in place through the aperture provided by the spacing of the left hand ends of the ribs 16 from the region of the catch 14, as illustrated in Figure 3 of the drawings.

The space below the transverse element 17, within the front cover 10 provides a receptacle for cigarettes or the like (not shown), the same being retained in place by a retainer plate 19 which has ears mounting swingably on a transverse axle 20 secured in the side walls 11 of the cover 10 and normally swung to a closed position by a conventional spring arrangement 21. On the upper end 7 of the main body is provided a pair of laterally spaced loops 22, to and between which extends a flexible carrying strap 23 like that possessed by a folding camera.

As indicated in Figure 1 of the drawings the front cover 10 in being opened exposes not only the calendar cards 18 and the cigarette retainer 19 and the cigarette compartment to be reached through forwardly swinging the plate 19, but the opening of the cover exposes the writing paper roll which is generally designated 24 and which consists of an ordinary roll of writing paper such as used in commercial calculating and adding machines, the same being wound from one roller to the other, located within opposite ends of the main body 5. A tearing arm 25 is hinged at the left hand side of the main body by a journal 26 receiving the bight portion of a U-shape 27 whose legs are anchored in a dummy wheel form 28 located at the upper left hand corner of the main body. A spring arrangement 29 cooperates with a hinge device to keep the arm 25 normally down-pressed in the position in which it is shown in Figure 1 of the drawings and in which its opposite extremity rests, as indicated by the numeral 30, on the edge of the opposite side wall 6 of the body 5 at a point just above or coincident with the upper edge of the writing table

31 which is supported on front and rear walls 32 and 33, respectively, which are spaced from the curved ends 7 and 8 of the main body and which extend across the main body between the side walls 6. The upper surface of the writing table 31 is only slightly depressed below the upper edge 9 of the side walls 6 as indicated in Figure 3 of the drawings. The writing table 31 likewise extends all the way across between the side walls 6 and the paper 24 rests flatly and slidably upon the upper surface of the writing table 31 from which it declines toward the spool 34 which is mounted on the winding shaft 35 which terminates in a winding wheel 36 which may or may not have the crank handle 37 suitably attached thereto at an eccentric point as indicated by the numeral 38. The shaft 35 has a stop collar 39 and inwardly of it a key 40 to cooperate with the semi-circularly cut-out portion 41 on the adjacent end of the spool 34 is non-rotatably connecting the shaft 35 and the spool 34. The spool 34 is provided with a longitudinal slot 42 into which the end of the paper 24 is inserted in order to wind the paper upon the spool 34 by rotating the winding wheel 36. The shaft 35 is journaled through the side walls 6 of the main body 5 at the upper part thereof as seen in Figure 1 of the drawings, with the wheel 36 on the right hand side for easy operation.

The opposite end of the main body accommodates the paper roll as it comes from the factory or distributor on a spool 34' which is, in turn, mounted on a shaft 35' which is journaled in the side walls 6 of the main body. Spring-pressed retarding means located within the curved end 8 of the main body press against the supply roll which is generally designated 44 to prevent the same from unwanted unrolling of the paper therefrom. Another friction retarding element 45 is similarly arranged in the opposite end of the main body to engage the gradually accumulating paper on the spool 34. Underneath the tearing arm 25 is a round stationary guide shaft 46 over which the paper glides from one roller to the other.

A winding wheel 36' is affixed to the shaft 35' at the lower end of the main body as shown in Figure 1 of the drawings for winding and re-winding purposes.

The bottom or back 47 of the main body is fully open between its side walls 6 between the points 48 and 49 to provide access to compartments behind the writing table 31, the said opening being closable by the rear cover which is generally designated 49 and which has a knob equipped latch 50 for enabling rotating the latch 51 into and out of position to hold the rear cover closed. On the inner side of the rear cover is a

channeled frame 52 which holds a mirror 53 in place which is accessible to view when the cover 49 is in the open position. A hinge arrangement 53 swingably connects the rear cover 49 with the edge of the mentioned opening in the back or bottom 47 of the main body. A shallow transverse wall 54 met by a longitudinal dividing wall 55 provides two laterally separated compartments for accommodating such articles as the head and the razor blades of a safety razor, as indicated by the dotted lines in Figure 2 of the drawings. A deeper transverse wall 56 spaced from the wall 54 provides a compartment for the reception of the handle of the safety razor or the like, and the space above the wall 56 and bounded at its top by the wall 32 provides space for odd articles.

A retainer bar 57 extends across the paper 24 at the lower end of the table 31 as indicated in Figures 3 and 1 of the drawings. One end of the bar 57 is provided with a handle 58 while the opposite end is provided with a loop 59 which is located at right angles to the bar and acts as an abutment against the outside of the left hand wall 6 when the adjacent end of the bar is inserted in a notch 60 formed in the upper edge of the side walls 6, with the opposite end of the bar inserted in a similar notch 61 formed in the opposite side wall 6, with the handle 58 also acting as an abutment, taking advantage of the flexibility of the walls 6, to hold the retainer bar 57 in place to insure the paper's being held in smooth writing condition on the table 31.

Although I have shown and described herein a preferred embodiment of my invention, it is to be definitely understood that I do not wish to limit the application of the invention thereto, except as may be required by the scope of the subjoined claim.

Having described the invention, what is claimed as new is:

A device of the class described comprising an elongated rectangular body including side and end walls, respectively, and a bottom, a shorter rectangular wall structure in said body arising from said bottom and forming with said side and end walls end walls in said body adapted to contain paper reels for feeding a memorandum strip from one to the other, said wall structure including a flat top forming a table over which said strip may be fed for writing thereon, and a turtle back hinged cover for said body forming when closed a space above the flat top for storage of articles therein, said cover having a swingable spring pressed plate therein coacting with the top of the cover to clamp articles therebetween.

ERIK WESTBERG.
